VANITY CASE

Filed May 15, 1929

FIG. 1.

FIG. 2.

Inventor

Walter F. Shelgren.

By *Edw. F. Shelgren Jr.*
Attorney

UNITED STATES PATENT OFFICE

WALTER F. SHELGREN, OF BRADFORD, PENNSYLVANIA

VANITY CASE

Application filed May 15, 1929. Serial No. 363,339.

The present invention relates to vanity cases of the type employing an endless belt for supplying a quantity of powder, rouge or the like exteriorly of a reservoir or container; and relates more particularly to a combined belt-fastener and finger tab by which the ends of the belt may be secured together and the belt may be easily moved or reciprocated.

10 The object of the present invention is the provision of a combined finger-piece and fastener of the type described which will be substantially of the same thickness as the material of the belt itself, thus occupying 15 no additional space in the vanity case and not requiring greater depth for the case; and which is neat in appearance and of such construction as permits of quick assembly or attachment to the belt and of economy in 20 manufacture.

With the above and other objects in view, the invention resides in sundry details of construction, combination and arrangement of parts hereinafter more fully described 25 and pointed out in the appended claims.

In the accompanying drawings which show the preferred form of the invention as at present devised:

Fig. 1 illustrates a vanity case equipped 30 with the combined finger piece and belt fastener of the present invention; and

Fig. 2 is a sectional view taken substantially on line 2—2 of Fig. 1 and illustrating the detailed construction of the combined 35 fastener and finger piece.

With particular reference to the drawings, C denotes a vanity case having a cover or top T and compartments for carrying powdered talcum and rouge. Endless belts B are associated with said compartments for delivering small quantities of the powdered contents of the compartments. These belts have one side extending into the compartments and another side lying exteriorly 40 thereof, so that when the belts are moved to bring the portion thereof lying within the compartment exteriorly of the compartment, a quantity of the contents of the compartment adhering to the belt is made accessible 45 to the user of the vanity case, this powder

or rouge being taken from the exposed surface of the belt by a puff or applicator. If further powder is desired, the belt is again shifted in opposite directions to repeat the operation.

It is desirable and practically necessary 55 for a finger piece to be provided by which the belt may be reciprocated. Since these belts B are made from straight pieces of material, it is also necessary to fasten the ends 60 of the strip in order to render the strip in endless form. These two requirements are accomplished in the present instance by a clip 10 made of sheet metal.

The clip 10 consists of a thin strip of 65 sheet metal of a length substantially the width of the belt. The side marginal edge portions of the strip are folded inwardly at 11 to lie flat against the body of the strip, and are then folded upon themselves as at 70 12 to provide two pair of gripping jaws 13 and 14 and a channel 15 between the points of fold 12, each marginal portion forming opposing jaws x and y opened along the outer side edges of the clip 10. To apply 75 the clip 10, thus formed, to a belt B, the ends of the belt strips may be dipped or coated with a cement or adhesive material, and then one end is inserted between the jaw 13 and the other end between the jaw 14. When 80 inserted the jaws of each marginal portion are crimped down upon the cemented end of the belt, thus tightly securing the ends of the belt to the clip 10.

The channel 15 provided between the marginal jaws of the clip is of substantial width and depth to receive the end of the finger, coin or other instrument by which the belt may be reciprocated in the manner above described, the inner ends 12 of the jaws forming abutments against which the finger nail or coin may bear.

The edges of the marginal portions may be folded inwardly as at 16, so that edge may act as a gripping surface on the inner sides of the jaws x of each pair as well as to finish off the edge of the jaw.

Since the clip may be made of extremely thin metal, it is obvious that it will lie flat and not occupy any greater space than the

thickness of the belt. It will also be obvious that the clip is a unitary article made from a single strip of metal and may be manufactured at a very low cost and be quickly assembled with the belt, making an extremely neat appearance and having a two-fold function.

Having thus described my invention, what I claim as new and desire to secure by Letters Patent of the United States is:

- 10 1. In a vanity case having a powder container, an endless powder conveyor movably arranged in the container and being capable of carrying powder from the container to a point where it may be removed from the conveyor, said conveyor comprising a strip of flexible material and fastening means securing the ends of the strip together, said fastening means being provided with a channel-like groove in its upper surface in which a finger or other instrument may be inserted for shifting the belt.
- 15 2. In a vanity case having a powder container, an endless belt movably arranged in the container for delivering powder from the latter to a point where it may be removed from the belt, said belt comprising a strip of flexible material, and a clip formed of relatively stiff material to provide two pairs of clamping jaws, each pair adapted to receive between it an end of said belt, said clip being further formed to provide a channeled groove between said jaws in which the finger or other instrument may be inserted to shift the belt.
- 20 3. A vanity case having a powder container, an endless belt arranged in said container for supplying powder therefrom when the belt is shifted, said belt comprising a strip of flexible material, a clip for securing the ends of said belt together, said clip consisting of a strip of metal having its marginal side edges folded inwardly upon the body of the strip and said marginal folded portions being bent intermediately upon themselves to form gripping jaws on opposite sides of the clip and opened along the side edges thereof for receiving the ends of said belt strip respectively, said jaws being pressed together to secure the belt thereto, said gripping jaws being spaced apart to form a channeled groove in which an instrument or finger may be inserted for shifting the belt.

In testimony whereof I have hereunto set my hand.

55 WALTER F. SHELGREN.
